UNITED STATES PATENT OFFICE.

GILBERT COMSTOCK, OF KEOUK, IOWA.

DESIGN FOR STOVE.

Specification forming part of Design No. 7,820, dated November 3, 1874; application filed September 1, 1874.
[Term of Patent 14 years.]

To all whom it may concern:

Be it known that I, GILBERT COMSTOCK, of Keokuk, Lee county, Iowa, have invented a Stove Design, of which the following is a specification:

The nature of this design is shown in the accompanying engravings, showing the stove referred to hereinafter.

The stove-body A is an oval or ovoid curved cylinder, arranged with sides overhanging a base, the axis horizontal, and the larger diameter of oval upright, as shown. It has a central urn on top, and any other suitable ornaments. These features, except the base, are not new. The end parts E E are wider and higher than the body, and have the new designs of form and ornament, all as shown. Their form has vertical sides and triparted top, with the parts tapering upward as triangles. They have top and bottom lines of horizontal moldings, T' V, and vertical side fields of lattice-work ornament L, surrounding the door in one of the ends, and peculiar side and top and face ornaments, H K I I' I'', for the top projections, all as shown. These projections above the body A are formed each of two parts, with backs riveted together, and presenting ornamented faces to each side, and giving strength to the parts. The door in one end has the peculiar ornamented border M, and ornamental central monogram consisting of the letters "C. B. & Co.", intertwined as shown. Below the stove, and separate from but supporting it, is base-plate T, extending beyond it on every side, to give a general relief and finish to the stove, while serving also as a low and convenient foot-warming rest on every side, at the two ends, and under the overhanging curved sides. Its outer edges have the curved and ornamental form as shown, to help in setting off the stove, and

in forming a desirable foot-rest and fender; and it is mounted on the ornamented legs X, the whole making a very unique and new style of appearance in this class of stoves.

I claim—

1. The stove design with base part T separate from and below the rounded cylindrical body A, substantially as shown.
2. The stove design with base part T below and surrounding the rounded cylindrical body A on all sides, substantially as shown.
3. The stove design with base part T below and around the rounded cylindrical body A at both ends, as shown.
4. The stove design with base part T on one side at the base of and under the overhanging rounded cylindrical body A, as shown.
5. The stove design with base part T, the ovoid cylindrical body A, and the end plates with three-parted tops, substantially as shown.
6. The stove design with the ovoid cylindrical body A and end plates with tops divided into three parts, with triangular outlines, substantially as shown.
7. The stove design with end plates having vertical sides and three-parted tops, substantially as shown.
8. The stove design with edge H, the top part K, and face figures I I' I'' V L, all combined substantially as shown.
9. The stove design with the ornamental border M, as shown.
10. The stove design with face figures I I', as shown.
11. The stove design with face figures V L, as shown.

GILBERT COMSTOCK.
